UNITED STATES PATENT OFFICE.

CHARLES CRISTADORO, OF ST. PAUL, MINNESOTA, ASSIGNOR TO THE WHIRLPOOL MIXER AND KNEADER COMPANY, OF SENECA FALLS, NEW YORK.

KNEADING AND MIXING MACHINE.

SPECIFICATION forming part of Letters Patent No. 738,663, dated September 8, 1903.

Application filed December 20, 1902. Serial No. 135,948. (No model.)

To all whom it may concern:

Be it known that I, CHARLES CRISTADORO, a citizen of the United States, residing at St. Paul, in the county of Ramsey and State of Minnesota, have invented certain new and useful Improvements in Kneading and Mixing Machines, of which the following is a specification.

My invention relates to improvements in kneading and mixing machines adapted especially for mixing and kneading substances of a plastic nature or in a plastic condition, such as dough, its object being to provide a machine wherein the material or materials shall be thoroughly mixed, compressed, kneaded, and aerated.

To this end my invention consists in the construction, combination, and arrangement of parts hereinafter described and claimed.

In the accompanying drawings, forming part of this specification, Figure 1 is a top view of the machine with the cover removed. Fig. 2 is an end elevation of the same looking toward the gear end with the drive-pulley omitted. Fig. 3 is a similar end view omitting the gears and drive-pulley, and Fig. 4 is a transverse vertical section taken on line *xx* of Fig. 1.

In the drawings, A represents a receptacle or trough supported upon legs 2. The bottom 3 and sides 4 of the trough are formed, preferably, with longitudinal corrugations upon the inside and merge into each other at the corners in a concave curve to form what may be termed for convenience of description a generally "U-shaped" bottom. Within the trough and near the bottom thereof are a pair of oppositely-working and longitudinally-corrugated kneading-rollers 5 and 5^a, mounted upon shafts 6 and 6^a, respectively. These rollers are arranged side by side and are so positioned with respect to each other and to the curved portions of the U-shaped bottom as to insure kneading coöperation not only between the rollers, but also between each roller and the adjacent bottom and side portions. In order that the spaces between the rollers and between each roller and the adjacent side of the trough may be accommodated in width to the character and thickness of the material to be kneaded, the roller-

shafts 6 and 6^a are preferably journaled in any suitable manner in adjustable and elastically-pressed bearings. As shown in the drawings, they are journaled in bearing-blocks 7 and 7^a, slidably supported between guides 8 and 9 upon the ends 10 of the receptacle. The bearing-blocks are adjustable in position relatively to one another by means of screws 11, threaded through the bars 12 at the ends of the guides and bearing against the plates 13, which are also slidable in the guides 8 and 9. The kneading-rollers 5 and 5^a may be held elastically against the spreading pressure of the material carried between them by spring means or other elastic instrumentality, such as the rubber cushion 14, (shown in the drawings,) interposed between each of the bearing-blocks and the adjacent plate 13.

Mounted upon the outer ends of the shafts 6 and 6^a are intermeshing gears 15 and 15^a, driven through the medium of the drive-pulley 16, mounted upon one of the shafts, from any suitable source of power. The gears 15 and 15^a are preferably of equal diameters in order that the kneading-rollers, which are themselves of equal diameters, may have the same peripheral velocity, and the gears and rollers are so arranged that the tongues 17 of the corrugations of one roller register with the grooves 18 of the corrugations of the other roller as the rollers are rotated toward each other, as indicated by the arrows in Fig. 4 of the drawings. The rollers are preferably of such diameters and so adjusted in position that the tongues of one roller would just clear the tongues of the other roller if the tongues registered instead of a tongue with a groove. To secure the best results, the corrugations of the bottom and sides are of less depth than the corrugations of the rollers.

To remove the partially-kneaded material from the rollers and to redistribute it and feed it again to the rollers, two screw conveyers 19 and 19^a are arranged in such proximity to the rollers, preferably above the same, that the edges of their flanges 20 and 20^a just clear the ends of the tongues upon the adjacent roller. As shown in the drawings, the conveyers are journaled in bearings 21 and 21^a upon the ends of the receptacle and are

rotated away from each other and oppositely to the adjacent rollers through the medium of the gears 22 and 22^a, which intermesh with the gears 15 and 15^a, respectively, upon the 5 roller-shafts.

To facilitate the removal of the material after it has been sufficiently treated, the bottom of the receptacle may be provided with any suitable door or doors, such as the outwardly-swinging doors 3^a, (shown in Fig. 4,) hinged to the bottom by hinges 23 and provided with suitable locking means, such as the eyes 24 and bolts 25. To afford convenient access to the rollers and other working 10 parts within the trough, one or both of the sides of the receptacle may be provided with any suitable door, such as the outwardly-swinging door 26, hinged to the side by a hinge 27. The receptacle is preferably provided 15 with a removable top or cover 28.

In use the material to be treated is fed to the center of the trough from above, so as to fall between the kneading-rollers. The corrugations of the rollers gather the material 20 from both sides and force it together and down through the narrowing space between the rollers into the triangular space 29 at the bottom and pack and compress it down therein until the space is full. At this stage the process 25 changes. The corrugated moving bodies now work against a corrugated fixed body, whereby the material is not only compressed, but is dragged, torn, and stretched into a stringy mass and thoroughly aerated. The material 30 is then carried around with the rollers until it reaches the screw conveyers. These are so geared as to have, preferably, the same peripheral velocity as the rollers. As they rotate they cut or scrape the dough or other 35 material from the rollers and carry it to the ends of the trough. As the conveyers turn in opposite directions, as indicated by the arrows in Fig. 4 and by the arrows upon the flanges in Fig. 1, the material scraped from 40 one of the kneading-rollers will be carried toward one end of the trough and the material scraped from the other roller toward the opposite end of the trough, so that the material is kept moving circularly around the trough. 45 At the ends where it accumulates and along the conveyers wherever they become over-loaded the material is again fed to the kneading-rollers and is subjected a second time to the process of kneading, mixing, pulling, and 50 tearing above described. The material may thus be subjected to the process an indefinite number of times, the operation being, indeed, continuous, so that the material is being constantly and successively acted upon for any 55 desired length of time in all the variety of ways necessary for the proper amalgamation of the materials and aeration of the mass.

It is obvious that the details of the device 60 may be modified in various ways without departing from the principle of the invention, the scope of which is defined in the claims.

Having now described my invention, what

I claim as new, and desire to secure by Letters Patent, is—

1. A kneading and mixing machine, comprising a pair of oppositely-working rollers disposed for kneading coöperation with each other, and means for scraping the kneaded material from the rollers and feeding it again to them near their place of kneading coöperation. 75

2. A kneading and mixing machine, comprising a trough having a corrugated bottom, and a pair of oppositely-working kneading-rollers rotatably mounted therein and disposed for coöperation with the corrugated bottom. 80

3. A kneading and mixing machine, comprising a trough having a corrugated bottom, and a pair of oppositely-working corrugated kneading-rollers rotatably mounted therein and disposed for kneading coöperation with each other and with the bottom. 85

4. In a mixing and kneading machine, the combination, with a trough, of a plurality of oppositely-rotating corrugated bodies disposed for kneading coöperation with each other whereby the material to be worked is compressed between them, and a stationary corrugated body arranged in proximity to the rotating bodies whereby the material is dragged by the rotating bodies over the corrugations of the stationary body for the purpose set forth. 95

5. A kneading and mixing machine comprising a trough formed with corrugations upon the inside, a pair of kneading-rollers adapted to compress between them the material to be kneaded and to carry it around with them in their rotation, and means for scraping the compressed material from said rollers and distributing it again to them near their place of kneading coöperation. 105

6. A kneading and mixing machine, comprising a trough having corrugated bottom and sides, and a pair of oppositely-working corrugated rollers rotatably mounted therein, the corrugations upon the bottom and sides coöperating with the corrugations upon the rollers, and a pair of screw conveyers arranged adjacent to the rollers and adapted to scrape the kneaded material from the rollers and convey it toward the ends of the trough. 110

7. A kneading and mixing machine, comprising a trough, a pair of oppositely-working corrugated rollers rotatably mounted therein and disposed for kneading coöperation with each other, and a pair of oppositely-rotating screw conveyers arranged in proximity to the rollers and adapted to scrape the kneaded material from the rollers and distribute it again to them near their place of coöperation. 120

8. A kneading and mixing machine, comprising a trough having a generally U-shaped corrugated bottom, and a pair of oppositely-working corrugated kneading-rollers rotatably mounted therein, said rollers being arranged relatively to each other so as to carry the material to be worked to the middle portion of the trough-bottom, and being so ar- 130

ranged relatively to the curved portion of the trough-bottom as to drag the material accumulated at the middle portion over the corrugations of the curved portion, substantially as and for the purpose described.

9. A kneading and mixing machine, comprising a trough having corrugated bottom and sides, a pair of kneading-rollers disposed for coöperation with each other and with the corrugated bottom and sides, said rollers being rotatably mounted in sliding bearings whereby they may be adjusted in position relatively to one another.

10. A kneading and mixing machine comprising a trough having corrugated bottom and sides, a pair of oppositely-working corrugated kneading-rollers arranged therein, elastically-pressed bearings for said rollers, and means for adjusting the bearings toward

20 and away from each other.

11. A kneading and mixing machine, comprising a trough having corrugations upon the inside, a pair of oppositely-working rollers mounted therein and disposed for kneading coöperation with each other and with the corrugations of the trough, and means for scraping the compressed material from the rollers.

12. A kneading and mixing machine, com-

prising a U-shaped trough, a pair of oppositely-working kneading-rollers mounted therein and disposed for kneading coöperation with each other and with the corner portions of the trough, and scraping means for removing the kneaded material from the rollers and feeding it again to them for further treatment.

13. A kneading and mixing machine, comprising a trough having a generally U-shaped bottom, the trough-bottom being corrugated at the corners, and a pair of oppositely-working kneading-rollers rotatably mounted therein, the rollers being arranged relatively to each other so as to carry the material to be kneaded to the middle portion of the trough-bottom, and being so arranged relatively to the corrugated corner portions of the trough-bottom as to compress and drag the material accumulated in the middle portions over the corrugations of the corner portions, for the purpose described.

In testimony whereof I affix my signature in presence of two witnesses.
